ENVELOPE FOR BANKING USE

Harlan M. Whitman, Minneapolis, Minn., assignor to Curtis 1000, Incorporated, St. Paul, Minn., a corporation of Minnesota

Filed July 13, 1959, Ser. No. 826,530

4 Claims. (Cl. 229—80)

This invention relates to mailing envelopes and more particularly to envelopes for use by banks to return bank statements, cancelled checks, etc. to depositors.

An object of primary importance of the invention is to provide an envelope for the above purpose with means to retain an addressed bank statement adjacent one end of the envelope and maintained in position relative to a window opening formed in the front panel of the envelope, the envelope also being adapted to retain a group of checks in position lengthwise of the envelope and against vertical movement.

A feature that enables the above object to be accomplished is that a strip of dry self-sealing latex or other gumming composition is positioned on the inside surface of the sealing flap, another strip of the same material being positioned on the inside surface of the front panel above the free edge of the back panel after folding so that sealing will be effected by pressing the latex gummed strip on the sealing flap into contact with the strip on the inner surface of the front panel.

Another feature of importance is that the gummed area on the inside surface of the sealing flap may be of sufficient width to contact and seal itself to a gummed strip on the outside surface of the back panel adjacent its free edge in addition to the inner portion of the gummed area on the sealing flap being sealed to the gummed strip on the inside surface of the front panel.

Another object of the invention, in a slightly modified embodiment of the invention, is to provide an area of standard gumming composition requiring moistening on the inside surface of the sealing flap, this area extending substantially the entire length of the flap, the inner portion or area of the sealing flap extending partially along the flap and being provided with a strip of self-sealing type gumming, there also being self-sealing gumming on the inner surface of the front panel but not on the outer surface of the back panel.

With the above and other objects in view, the invention may include the features of construction and operation set forth in the following specification and illustrated in the accompanying drawings.

In the accompanying drawings annexed hereto and forming a part of this specification, I have shown the invention embodied in envelopes of usual business form and adapted for particular forms of enclosures such as bank statements and checks, but it will be understood that the invention may be otherwise embodied and that the drawings are not to be construed as defining or limiting the scope of the invention, the claims appended to this specification being relied upon for that purpose.

In the processing of depositors' accounts by banks, increased use is now being made of mechanical business machines and equipment, the result being that typed statements are periodically mailed to depositors with a tabulation of the deposits made and checks drawn. The depositor's identification card, if such cards are used, and the cancelled checks also may be enclosed. The statement, folded to properly position the depositor's name

2

and address, is placed within a window envelope so that the name and address may be visible through the window. Cancelled checks extending substantially the full length of the envelopes without folding also are placed in the envelope. As the folded height of the statement and identification card is or may be materially greater than the width of the checks, means are required to prevent up and down movement of the checks within the envelope. Also the statement must be prevented from movement laterally 10 away from the window for its address.

The retaining of the statement, checks, etc. in their proper relative positions is accomplished by the envelopes shown in the figures of the drawing in which:

Fig. 1 is the inside surface of an unfolded blank of an envelope made according to the present invention;

Fig. 2 is an envelope made from the blank shown in Fig. 1 before sealing and showing a statement and checks in position within the envelope;

Fig. 3 shows an envelope made according to the present invention with the statement and checks inserted and the envelope sealed ready for mailing; and

Fig. 4 shows a slightly modified form of envelope, made according to the present invention from a blank shown in Fig. 1, after having been folded and the end 25 flaps gummed to the rear panel.

In the above mentioned drawing there have been illustrated one embodiment of the invention and a slightly modified form thereof which are now deemed preferable, but it is to be understood that changes and modifications 30 may be made within the scope of the appended claims without departing from the spirit of the invention.

Referring more in detail to the figures of the drawing and first to Fig. 1, it will be seen that the blank from which the envelopes are formed is of generally conventional outline. The central or front panel 10 is provided with a window 12, the size and position of which are determined by the position of the name and address on the previously addressed statement to be enclosed. Extending from one side edge of panel 10 is a back panel 14, the width of which is somewhat less than the height or width of the front panel 10. End flaps 16 extend from opposite ends of the central panel 10 and from the side opposite that from which the back panel 14 extends is a sealing flap 18.

In making the envelope the end flaps 16 are folded inwardly and the back panel 14, the end portions of which have been gummed, folded over and sealed thereto in the usual manner. In this operation the gum used on the end portions of the back panel 14 is or may be conventional and adhere directly to the ungummed end flaps 16.

With the back panel gummed to the end flaps in the embodiment of the invention shown in Figs. 1, 2 and 3, self-sealing dry gumming is applied as shown at 20 to the inside surface of the sealing flap. Similar self-sealing 55 gumming 22 is applied to the free edge of the outer surface of the back panel 14 and, as shown at 24, to the inside surface of the front panel 10 above the free edge of the back panel 14. The width of the strip 20 of the self-sealing gumming applied to the inner surface of the sealing flap 18 is of sufficient width to cover ample areas to effect a good seal with self-sealing areas 22 and 24. When in sealing position the outer portion of the gumming 20 on the sealing flap 18 contacts the strips 22 of gumming on the back panel 14, the inner portion of area 60 20 sealing with the strip 24 on the inner surface of the front panel 10.

If preferred, two adjacent narrow strips of self-sealing gummed areas on the sealing flap 18 may be substituted for the single wide strip. This is indicated by the dotted lines extending through area 20 in Fig. 2.

A characteristic feature of this dry self-sealing composition is that it will adhere only to the same material

when the similarly gummed areas are pressed firmly one against the other. These dry self-sealing gummed surfaces do not, however, adhere to any surface untreated with similar material. No adhesion therefore takes place between an area gummed with this dry sealing composition and ungummed surfaces of the envelope or with the surfaces of the statement, checks or other enclosed material.

In preparing the envelope for mailing, the statement 26 and checks 28 as shown in Fig. 2 are placed within the envelope and the sealing flap 18 is then pressed against the gummed area 22 on the back panel 14 to seal the envelope. The gummed strip 24 on the inside surface of the front panel 10 adheres to the inner portion of the gummed strip 20 on the sealing flap 18. The adhering together of these two surfaces 20 and 24 divides the space within the envelope into compartments, one at one end of the envelope for the statement 26, the other extending the full length of the envelope for the checks 28. The statement 26, folded to extend the entire width or height of the envelope cannot move laterally by reason of the gumming applied to the free portion of the inner surface of the front panel 10 adhering to the gumming on the sealing flap 18. The checks 28, extending the full length of the envelope, cannot move upward for the same reason. The dry self-sealing gummed areas do not adhere to the statement 26 or to the checks 28. The outer portion of strip 20 of gumming on the sealing flap 18 adheres to the area of gumming 22 on the outer surface of the back flap 14 over its entire length and effectively seals the envelope in the conventional manner.

Referring to Fig. 4 the envelope blank is in every way similar to the blank shown in Fig. 1, and has a window opening (not shown) similar to opening 12 in Fig. 1. However, the sealing flap has two strips of gumming, 30 and 32, the inner one 32 being of the self-sealing type which adheres on pressure to the gummed strip 34 on the inner surface of the front panel. The outer strip 30 on the sealing flap is of conventional type which after being moistened will adhere to an ungummed area 36 on the outer surface of the back panel 14. The only areas of self-sealing gum in this modified form of the invention are the inner area 32 on the sealing flap 18 and area 34 of the inner surface of the front panel 10. The outer strip 30 of gumming on the sealing flap 18 in this modified form and on the opposite ends of back panel 14 are of the conventional gumming. The sealing of this modified form of envelope therefore requires moistening of the gumming 30 in the conventional manner.

I claim as my invention:

1. A banking envelope comprising a front panel, a back panel, end flaps for sealing the ends of said panels together, a gummed sealing flap extending from the long

edge of said front panel and extending when folded over a portion of said back panel, an area of dry sealing composition on said sealing flap, and an area of similar sealing composition on the inside surface of the front panel above the edge of said back panel, whereby when said sealing flap is folded said areas of gumming are adapted for sealing contact throughout their gummed areas.

2. A banking envelope comprising a front panel, a back panel, end flaps for sealing the ends of said panels together, a sealing flap extending from the long edge of said front panel and extending when folded over a portion of said back panel, a wide area of dry sealing composition on said sealing flap, areas of similar sealing composition on said back panel and on the inside surface of the front panel above the edge of said back panel, whereby when said sealing flap is folded said gummed area on said sealing flap is in sealing contact with the gummed areas on said back panel and inside surface of said front panel.

3. A banking envelope comprising a front panel, a back panel, end flaps for sealing the ends of said panels together, a sealing flap gummed along the free edge of its inner surface and extending from the long edge of said front panel and adapted when folded to extend over a portion of said back panel, an area of dry sealing composition on an intermediate portion of said sealing flap, an area of similar sealing composition on the inside surface of the front panel above the edge of the back panel and an area of similar sealing composition along the free edge of said back panel, whereby when said sealing flap is folded said gummed area on said sealing flap is in sealing contact with the gummed areas on said back panel and inside surface of said front panel.

4. A banking envelope comprising a front panel, a back panel, end flaps for sealing the ends of said panels together, a sealing flap extending from the long edge of said front panel and extending when folded over a portion of said back panel, a wide area of dry sealing composition on the inner surface of said sealing flap, areas of similar sealing composition on the outside surface of said back panel and on the inside surface of the front panel above the edge of the back panel, whereby when said sealing flap is folded a portion of said area on said sealing flap will contact the gummed area on said back panel and another portion thereof will contact the gummed area on the inside surface of said front panel.
